UNITED STATES PATENT OFFICE

102,035

DESIGN FOR A TABLE

Arthur E. Meyerhoff, Chicago, Ill.

Application October 12, 1936, Serial No. 65,267

Term of patent 14 years

To all whom it may concern:

Be it known that I, Arthur E. Meyerhoff, a citizen of the United States, residing at Chicago, in the county of Cook and State of Illinois, have invented a new, original, and ornamental Design for a Table, of which the following is a specification, reference being had to the accompanying drawing, forming a part thereof.

Figure 1 is a perspective view of the table embodying my new design, taken from the front;

Figure 2 is a perspective view, on a reduced

scale of the table shown in Figure 1, but taken from the rear;

Figure 3 is a top plan view of the table as shown in Figure 2;

Figure 4 is a rear elevation of the table as shown in Figure 2; and

Figure 5 is a side elevation of the table as shown in Figure 2.

I claim:

The ornamental design for a table, as shown.

ARTHUR E. MEYERHOFF.
